Attorney

UNITED STATES PATENT OFFICE.

FRANK H. NASH, OF LA FAYETTE, GEORGIA, ASSIGNOR TO NASH AUTO ACCESSORY MANUFACTURING COMPANY, OF LA FAYETTE, GEORGIA.

PROTECTOR FOR AUTOMOBILE TOPS.

Application filed July 5, 1922. Serial No. 572,896.

To all whom it may concern:

Be it known that I, FRANK H. NASH, a citizen of the United States, residing at La Fayette, in the county of Walker and 5 State of Georgia, have invented certain new and useful Improvements in Protectors for Automobile Tops, of which the following is a specification, reference being had to the accompanying drawings.

10 This invention relates to devices adapted to be disposed upon the bows of automobile tops for the purpose of keeping the top tight and preventing it from bagging.

A further object of the invention is to 15 provide a device of this character which is adapted to be disposed between the middle bow of the automobile top and the cover and which prevents the tacks from working out of the bow lining and prevents the lining 20 from wearing out or becoming loose, this device further protecting the material of the top from beating out on the bows or coming in contact with the tacks.

A still further object is to provide a device 25 of this character which will prevent or deaden the vibrations of the bow relative to the cover so that the material of the top will not stretch or jerk on the back curtain.

30 Other objects will appear in the course of the following description.

My invention is illustrated in the accompanying drawings, wherein:—

Figure 1 is a fragmentary elevation of the 35 bow of an automobile top, the cover of the top being shown in section, my device being shown as applied thereto;

Figure 2 is a section on the line 2—2 of Figure 1;

40 Figure 3 is a face view of the strip 11; Referring to these drawings, 10 designates the middle bow of an automobile top which is, of course, of the usual construction. Disposed upon the outer edge face of the 45 bow is a metallic strip 11 having lugs 12 at intervals which are bent down at right angles to the body of the strip so as to embrace the side faces of the bow and be clamped thereto by tacks 13. Disposed

50 above this metal strip and resiliently supported therefrom is a longitudinally extended, metal cap 14 U-shaped in cross sec-

tion and open at its ends, the corners of the cap being rounded, as at 15.

Disposed between the inner face of this 55 cap and the upper face of the strip 11 are a plurality of leaf springs 16, these springs being preferably V-shaped so as to provide two arms, one of which arms is attached at its extremity to the metallic strip 11 and the other attached to the upper wall of the cap 14. The metal cap 14 is preferably covered, at least as regards its upper face, with a layer of felt 17. The springs urge 60 this cap 14 upward against the material 65 of the cover 18 and hold this cover taut.

The device is intended to be mounted on the top of the middle bow or bows of the automobile top between pads and acts to level the top cover and keep the tacks in 70 the bows from working out of the bow lining, and prevents the lining from wearing out or coming loose. Inasmuch as the material of the top is lifted off of the bow 10, the material of the top will be protected 75 from beating out on the bows or coming in contact with the tacks. Furthermore, the material of the top will be held taut and prevented from bagging. This device helps 80 to take care of the bow vibrations so that 85 the material of the top will not stretch nor jerk on the back curtain. About 90% of all the tops become damaged by the material of the top or cover cutting or wearing out where they are loose over the middle bows, and this device entirely prevents this action.

I claim:—

1. An attachment of the character described comprising a supporting strip 90 adapted to be attached to and extend longitudinally of the upper edge face of the bow of a vehicle top, a member U-shaped in cross section and adapted to bear against the under face of the cover of the vehicle 95 top and having sufficient width whereby it may embrace the bow when fully depressed, and springs each attached at one end to said supporting strip and at the other to said member and resisting the downward 100 movement of the member.

2. An attachment of the character described comprising a supporting strip adapted to rest upon the upper edge of a

vehicle top bow and having lugs adapted to embrace the side faces of said bow and be attached thereto, a cover supporting body ¹⁰ U-shaped in cross section and having a width greater than the strip, and V-shaped springs, each spring having one end mounted upon the strip and the other end en-

gaging the inner face of the body and resisting movement of the body toward the strip.

In testimony whereof I hereunto affix my signature.

FRANK H. NASH.
